UNITED STATES PATENT OFFICE

2,220,188

TROUSER SUPPORTER

Ernst Wischan, Drexel Hill, Pa.

Application November 29, 1938, Serial No. 242,949

1 Claim. (Cl. 2—237)

This invention relates to improvements in trousers and has as its principal object the provision of a belt-type support which is so incorporated in the waist band of the trousers that it is entirely concealed from view and which is characterized by the provision of means for so adjusting the effective length of the belt as to snugly and comfortably fit the trousers about the waist of its wearer.

10 A further object of the present invention is to provide a built-in waist band support for trousers to thereby eliminate not only the necessity of employing separate external belts for supporting the same but also the use of the more or less unsightly belt loops which are so conventional in trousers.

Still another and important object of the present invention is to provide a built-in waist band support for trousers of such character that there is no tendency for the waist band of the trousers to buckle, the concealed support functioning to maintain the waist band smooth and unruffled in appearance at the same time that it efficiently supports the trousers with no visible evidence of any supporting means, thereby rendering the trousers as worn by the wearer more comfortable in fit and more sightly in appearance.

Still other objects will be apparent more fully hereinafter, it being understood that the present invention consists substantially in the combination, construction, location and relative arrangement of parts, all as will be described more fully hereinafter, as shown in the accompanying drawing and as finally pointed out in the appended claim.

In the accompanying drawing:

Figure 1 is a perspective view of the waist portion of a pair of trousers or similar garment constructed in accordance with and embodying the principles of the present invention;

Figure 2 is a somewhat similar view on an enlarged scale and with parts of the trousers broken away, the front of the trousers being shown open;

Figure 3 is a sectional view taken on the line 3—3 of Figure 2;

Figure 4 is a sectional view taken on the line 4—4 of Figure 2; and

Figure 5 is a sectional view taken on the line 5—5 of Figure 1.

Referring now more particularly to the drawing, it will be observed that the present invention is illustrated as being embodied in a pair of trousers, designated generally by the reference numeral 10, although it will be understood that the

invention is applicable to any other type of outer garment which opens at the front and is adapted to be supported upon the waist of the wearer. As clearly appears in the drawing, the waist band 11 of the garment 10 is of substantially tubular or tunnel construction throughout, this construction being formed essentially of an inner lining strip 12 which is secured along its upper and lower edge by lines of stitching 13 and 14 to the inner surface of the upper portion 15 of the fabric of 10 which the trousers is principally made. Preferably, the upper edges of the fabric 15 and the lining 12 as well as the lower edge of the lining 12 are inturned to provide finished edges, the lines of stitches 13 and 14 passing through said in-turned portions to secure the lining 12 in the desired relation to the fabric 15, it being noted that this construction provides a space between the lining 12 and the outer fabric 15 within which may be accommodated a flat belt 16 or other supporting device.

This flat belt 16 may be formed of any suitable material, preferably a woven textile material of sufficient body and stiffness that when it is inserted in the space between the outer fabric 15 and its inner lining 12, it supports the waist band of the trousers against any tendency to buckle or become ruffled. To that end, the inserted belt 16 is of a width to more or less completely fill the space provided between the vertically spaced lines 30 of stitching 13 and 14 of the waist band.

As most clearly appears in Figure 2, one end of the inserted supporting belt 16 is securely fastened, as at 17, to the waist band by any suitable means, preferably by sewed stitches. Immediately adjacent this secured end 17 of the insert belt is a metal fastener or catch element 18, the central body of which overlies the outer face of the waist band fabric 15 and is spaced therefrom sufficiently to permit it to be engaged by a coacting metal hook element, such as at 19, which is secured to the opposite end or extremity of the inserted belt 16.

These metal elements 18 and 19 are generally known in the art as hook and eye elements and are often conventionally employed in trousers in lieu of a button and button hole to close the front flap of the trousers. In this case, however, these elements 18 and 19 are each of a vertical dimension approximately equal to the width of the inserted belt 16 so that they cooperate with the latter to rigidify and prevent buckling or curling of the front portion of the waist band. Preferably, the hook type fastening element 19 is so secured to the extremity of the waist band that the only 55

portion thereof which is exposed is the reversely bent hook 20 which is adapted to engage the metal eye 18. It will be understood, of course, that the end of the inserted belt 16 to which the hook element 19 is connected is secured within the corresponding end of the waist band in any suitable manner, preferably by the same sewed stitches 21 which secure the hook element 19 in place. It will also be understood that the hook 10 and eye elements 18 and 19 are relatively so arranged that when they are engaged to fasten together the extremities of the waist band, no part of these fastening elements is visible to the eye.

In order to adjust the waist band of the trousers to snugly and comfortably fit about the waist of the wearer, the inserted belt 16 is preferably provided with means for adjusting the effective length thereof, this means being shown most clearly in Figures 1 and 2. As appears most clearly in Figure 1, the inner lining 12 of the waist band is provided with a portion 22 the lower edge of which is free to be lifted away from the outer fabric 15 and so provides in effect a pocket 23 within which is located a clamp type 20 adjusting means 24 for adjusting the length of the belt 16. This adjusting means may be of the well-known suspender type or any other type suitable for the purpose and is secured to the rear extremity of the belt section 16^a which is separate from a cooperating belt section 16^b. In the arrangement shown, it will be apparent that as the belt sections 16^a and 16^b are longitudinally adjusted relatively to each other, the effective length of the belt 16 is altered as desired to snugly 35 and comfortably fit about the waist of the wearer. Once this adjustment is made and the belt sections 16^a and 16^b are secured together by the clamp 24, no further attention need be given to the belt. As appears most clearly in Figure 1, the freely extending extremity 16^a of the belt section 16^b may be disposed in the waist band in 40 such manner that it overlies the belt portion 16^a

and is secured neatly and flatly in position. While the pocket portion 23 of the waist band in which is disposed the adjustable clamp or buckle 24 is shown in Figure 1 as being located at the rear of the trousers, it will be understood, of course, that this pocket, and accordingly the adjusting clamp or buckle, may be located at any other desired point in the waist band, as, for example, at either side thereof.

It will be understood, of course, that the invention is susceptible of various changes and modifications which may be made from time to time without departing from the real spirit or general principles thereof, and accordingly it is intended to claim the same broadly, as well as specifically, as indicated in the appended claim.

What is claimed as new and useful is:

In an article of wearing apparel, a waistband, a waistband support comprising a belt of relatively stiff material composed of two separate parts having their rearwardly extending ends arranged in parallel overlapping relation and together extending circumferentially about and encased in the waistband of the article, the frontal extremities of the belt parts being respectively fixedly secured to the corresponding frontal extremities of said waistband, hook-and-eye fastening elements respectively secured commonly to the front extremities of said belt parts and the corresponding extremities of said waistband, said fastening elements being adapted for quick-detachable engagement to close the open front of said article at the waist line thereof, and a friction grip clamp concealed within the waistband and engaging the overlapping parts of said belt to adjust the circumferential length thereof, said belt being completely concealed from view within the said waistband and being of a width substantially equal to that of the waist band whereby buckling of the latter is prevented.

ERNST WISCHAN.
